UNITED STATES PATENT OFFICE.

CATHERINE O'HARA, OF NEW YORK, N. Y., ASSIGNOR TO THE BUTTERICK PUBLISHING COMPANY, (LIMITED,) OF SAME PLACE.

DESIGN FOR A LADY'S COSTUME.

SPECIFICATION forming part of Design No. 14,508, dated December 25, 1883.

Application filed October 27, 1883. Term of patent 3½ years.

To all whom it may concern:

Be it known that I, CATHERINE O'HARA, of the city, county, and State of New York, have invented and produced a new and original Design for a Pattern of a Lady's Costume, (numbered 8,932;) and I do hereby declare that the engraved prints accompanying this specification convey to any one accustomed to using paper patterns a clear understanding of how to a garment made up by the pattern will appear.

The design shows a short walking-skirt, having a deep broad panel on the front and narrower panels of similar depth at the sides, displaying pointed straps at their flaring edges, and shows also a basque that is closely fitted

to the figure, and is of medium depth at the front and sides, and has its back deepened and widened below the waist-line to form the back drapery, which is draped at the center by 20 plaits. Coat sleeves and a standing collar are added.

What I claim as my invention, and desire to secure by Letters Patent, is—

The design for a lady's costume, as shown in 25 the engraved prints accompanying this specification.

CATHERINE O'HARA.
